COMBINED FILTER AND VALVE FOR
GASEOUS FUEL

Ervin H. Mueller, Grosse Pointe, Mich.

Application December 4, 1947, Serial No. 789,635

3 Claims. (Cl. 183—39)

1

This invention relates to a combined filter and valve especially for the purpose of filtering and controlling the supply of gas for a pilot flame of gas burning equipment.

Because of the small passages and the small flame of a pilot burner, it is desirable to filter the gas in order to entrap included matter, such as carbon or the like, which may otherwise tend to clog such passageways. At the same time it is desirable to have a control over the supply of gas in order that the size of the pilot flame may be regulated and so that when necessary or desirable the supply of gas may be completely shut off.

It is the particular object of this invention to provide a filter for the above purposes which can be easily and cheaply manufactured so that it can be furnished to the trade at a low cost and to incorporate in the construction a valve construction for regulating the flow of gas. The idea is to employ a combination construction in the sense that the valve is incorporated in the filter housing in such a way as to materially reduce manufacturing cost and simplify the construction to the end that a separate valve housing is not needed. To this end a valve arrangement of unusual construction, which rather radically departs from the practice heretofore of providing a separate valve member and housing therefor, is incorporated in the filter housing. This construction resides essentially in but two added elements and yet an efficient low cost structure is provided.

The structure shown in the accompanying drawings illustrates one form of the invention.

Fig. 1 is a general view rather schematic in form illustrating the top burners of a gas range and showing the pilot and filter and valve arrangement.

Fig. 2 is an enlarged cross sectional view taken substantially on line 2—2 of Fig. 1 showing the filter and valve arrangement.

Fig. 3 is a plan view of the filter and valve assembly.

Fig. 4 is an enlarged perspective view of the valve body or block.

Fig. 5 is an enlarged partial cross sectional view showing the valve structure in metering position.

A top burner arrangement for a gas range is illustrated in Fig. 1 as having a top surface member 1 and four burners 2 which receive their gas from a suitable pipe or manifold 3 with each burner controlled by its controlling valve 4. Rather centrally positioned with respect to the four burners is a pilot housing 6 for a pilot flame to which gas is supplied by a conduit 7. Flash 55

2

tubes 8 extend from the pilot housing 6 to a point in proximity to each burner. The top member 1 is cut away to demonstrate the pilot housing. Suffice it to say that a pilot flame burns constantly in the pilot housing 6 and when gas is supplied to one of the burners 2 by the opening of its valve 4 some of the gas flows through a flash tube, is ignited by the pilot flame and the resultant flashback ignites the gas issuing from the burner. This is all well known to those versed in the art and no further description seems to be necessary.

As shown in Fig. 2 the filter and metering and control valve is disposed between the main supply pipe or manifold 3 and the conduit or tube 7. The filter body preferably takes the form of a member 10, which may be fashioned from sheet metal as by means of a drawing operation, having a hollow body portion 11 and a smaller screw threaded portion 12 arranged to be threaded into the manifold 3. A second body portion has a relatively large part 13 which slidably fits within the portion 11, a tapered part 14, an intermediate portion 15 and a threaded extension 16 adapted to receive a coupling nut 17 for the attachment of the conduit 7 thereto. The intermediate portion 15 is conveniently of hexagonal form. This is convenient in the manufacture of the elements and it provides a nut formation for the reception of a wrench.

Within the relatively large portions of these members is disposed a body of filtering material 20 preferably held in place by screens or suitable porous material 21 and 22. The screen 21 may abut against a washer 23 while the screen 22 may be positioned by a ring-like element 24 which abuts against a washer 25. When these parts are thus assembled the edge 26 of the portion 11 is spun over the tapered part 23 to thus hold the two elements in assembly. This provides for the filtering of the gas as it flows therethrough from the conduit 3 to the tube 7.

In order to provide a controlling valve a body or block, as shown at 30, is provided. This body or block may be obtained from hexagonal bar stock, preferably brass, which is cut off into sections of the desired length for fitting into the intermediate hexagonal portion 15. This valve body is, of course, inserted into position before the assembly is made as above described and it is preferably abutted against a washer 31. The purpose of the washer 31 is to insure that all gas flowing to the pilot must pass through the passages and ports in the body and not around the body.

The block is provided with a passage for gas

which includes an inlet passage 35 which may be angularly disposed and this intersects a passage 36 which is formed in the block from one of its faces, as shown in Fig. 4. The block is also provided with an outlet passage or port 37 which communicates with the passage 36. The block is provided with a threaded hole in alignment with the passage 36 and a tapered seat 38 is at the junction of the hole and the passage 36. The side 15a of the hexagonal intermediate part is provided with an opening in alignment with the hole 38 for the reception of a valving screw 40 which has a head 41 for receiving a suitable tool, such as a screw driver, and which preferably has a spring 42 interposed between the head and the wall 15a. The inner end of the screw is tapered to provide a valving portion as at 43 by which the passage or port 36 may be metered or closed when the tapered end 43 is adjusted to engage the seat 38.

The passages and the opening in the block 30 may be formed by drilling operations and these drilling operations are preferably performed on the block before it is inserted in the intermediate portion 15. The internal threads in the block may or may not be formed thereon before the block is inserted in position. The hole in the face 15a may be formed before or after the block is inserted. The hole in the face 15a may be formed by a drill after the block is inserted with the same drill passing into the block to enlarge the opening therein and the hole and the opening may both then be internally threaded as shown. Thus, by these simple expedients an effective metering and shutoff valve is provided in conjunction with a filter. The screw not only serves as a valving agency and metering agency but serves to lock the valve block in position.

I claim:

1. A combined filter and valve structure adapted for use with gas for a pilot flame comprising, two cup shaped members telescoped together to form a chamber, filtering material in the chamber, one member having an extension for connection to a source of gas supply, the other member having an extension for connection to a conduit for carrying the gas to a pilot burner, one of said members having a hollow intermediate portion, a separate block of metal situated in said portion, said block of metal having a passage therethrough for the flow of gas, a side wall of the intermediate portion and the block of metal having aligned openings therein with the opening in the block of metal intersecting said passage, the said opening in the block of metal having internal threads, and a valving screw threaded into the opening in the block of metal and passing out through the opening in said intermediate portion, said valving screw having an inner end for metering the passage through the block of metal.

2. A combined filter and valve structure adapted for use with gas for a pilot flame comprising, two cup shaped members having relatively large portions telescoped together to form

a chamber, filtering material in the chamber, one cup shaped member having a relatively ensmalled extension for connection to a source of gas supply, the other member having a relatively ensmalled extension for connection to a source of gas supply, the other member having a relatively ensmalled extension for connection to a conduit for carrying the gas to a pilot burner, said other member having a hollow intermediate portion of intermediate dimensions located downstream from the filtering material, a separate block of metal positioned in said intermediate portion, said block of metal having a gas flow passage therein formed to provide a valve seat, the block of metal and the wall of the intermediate portion having aligned openings with the opening in the block of metal intersecting the passage, the opening in the block of metal having internal screw threads, and a valving screw passing through the opening in the intermediate portion and threaded into the block of metal and having a valving end portion arranged to meter and to seat upon the valve seat formation in said passage.

3. A combined filter and valve structure adapted for use with gas for a pilot flame comprising, two cup shaped members of formed sheet metal having relatively large portions telescoped together to form a chamber, filtering material in the chamber, one member having an extension for connection to a source of gas supply, the other member having an extension for connection to a conduit for carrying the gas to a pilot burner, said other member having a hollow intermediate portion located downstream from the filtering material, said intermediate portion having cross dimensions less than that of the chamber and being substantially hexagonal in cross section, a hexagonal metal body seated in said intermediate portion, said body having a passage therethrough so formed and shaped as to provide a seat, the metal body and the wall of the intermediate portion having aligned openings with the opening in the body intersecting the passage, the opening in the body being screw threaded, and a screw member passing through the opening in the intermediate portion and threaded into the opening in the body and having an end portion arranged to co-operate with the valve seat to meter and to close the passage.

Patent No. 2,506,313

ERVIN H. MUELLER

It is hereby certified that error appears in the printed specification of the above numbered patent requiring correction as follows:

Column 4, lines 4 and 5, strike out the words and comma, "the other member having a relatively ensmalled extension for connection to a source of gas supply,"; and that the said Letters Patent should be read as corrected above, so that the same may conform to the record of the case in the Patent Office.

Signed and sealed this 5th day of December, A. D. 1950.
